UNITED STATES PATENT OFFICE.

EDWIN E. SLICK, OF PITTSBURG, PENNSYLVANIA.

DOUBLE-END DUMPING-CAR.

No. 892,318.

Specification of Letters Patent.

Patented June 30, 1908.

Application filed January 15, 1908. Serial No. 410,889.

To all whom it may concern:

Be it known that I, EDWIN E. SLICK, a citizen of the United States, residing at Pittsburgh, in the county of Allegheny and State of Pennsylvania, have invented certain new and useful Improvements in Double-End Dumping-Cars, of which the following is a full, clear, and exact specification.

This invention relates to double-end dumping cars, and has particular reference to the construction of a car frame and the mounting of a car body thereon whereby it may be dumped at both ends of the car body, instead of at one end only, as such cars have heretofore been constructed.

The type of car to which this invention relates is that known as cinder or slag cars, comprising an under frame and mounted thereon a tilting ladle or body forming the car body.

This invention is particularly concerned with cinder cars of the type wherein the ladle is dumped at the end, and has for its object to enable the car body to be dumped in opposite directions towards either end of the frame.

With the type of single end-dumping cars in common use at foundries and blast furnaces, it is necessary to have it in a certain position at the end of the train, and also such cars can only be drawn from the end opposite the dumping end, thereby requiring considerable switching and turning around.

According to this invention, an end dumping car is provided which can be turned to discharge its contents at either end of the car body, as may be desired, and which can be coupled to other cars or a locomotive at either end, thereby permitting greater facility of handling and operation.

The invention with reference to one form thereof is shown in the accompanying drawings, wherein

Figure 1 represents a side view in elevation of a dumping car embodying the invention; Fig. 2, a top plan view; Fig. 3 an end elevation; and Fig. 4 a detail of the car body actuating mechanism.

The car frame is composed of side members 1, 1, connected by end members 2, 2, which latter will be provided at each end with the draft rigging and train couplings 3, 3. The side members 1 and end members 2 are rigidly secured together and braced, as may be found necessary to form the under frame proper, providing an interior unobstructed space in

which the car body or ladle 5 can be moved longitudinally in either direction from a central upright position and tilted to discharge the contents below the track and between the side frames 1.

As herein shown, the car body is of the tilting and bodily movable type, the body proper being mounted on trunnions 8 which roll on tracks 9 carried by the side frames 1 and simultaneously tilt the car body. Rigid with the trunnions 8 are gears 10 which roll on fixed racks 11, also carried by the side frames 1.

In order to actuate the car body hand dumping mechanism is provided, which is mounted on one side of the car frame and capable of being actuated from either end of the car body. As herein shown, one of the side frames 1 is provided with a pair of brackets 12, having uprights 13, in which a longitudinally extending screw-shaft 14 is mounted, and having thrust collars 15 at either end. This screw-shaft 13 works through a nut or block 17, having a removable cap plate 18, and also a socket or box in which the reduced end 19 of one of the trunnions 8 engages, so that when the screw-shaft 14 is turned the nut 17 will be reciprocated and thereby actuate the trunnions to roll on the tracks 9 and gears 10 on the racks 11. In order to actuate the screw-shaft 14 a shaft 21 is mounted in the brackets 12 and provided with hand-wheels 22 at each end, so that the car can be dumped from either end. The shaft 21 is geared to the screw-shaft 14 by means of pinions 23, 24, and 25, so that by turning the hand-wheels 22 the screw-shaft 14 will be turned and thereby operate the car body.

By reason of the worm-actuating connection, there will be no back thrust from the car body upon the actuating mechanism tending to turn the hand wheels, and also the use of fastenings for holding the car in upright position may be dispensed with inasmuch as the car body will not tend to oscillate on the trunnions. One or the other of the hand wheels will be operated to dump the car, according to the end at which it is to be dumped, and preferably at the opposite end away from the heat.

As herein shown, the car body is made oval in cross-section so as to increase the carrying capacity, inasmuch as the transverse diameter must be such as to permit the top of the body to pass between the sides of

the frame when being dumped, and the width of the frame is limited by the gage of the railroad. It is not intended to restrict this invention to an oval bowl, but such a bowl will have a greater carrying capacity than would a round bowl of the same transverse diameter. As will be seen from Fig. 1, the underframe is mounted on four wheels, the axles of which are carried in boxes which slide vertically in the depending portions 27 of the side frames 1 with interposed springs, and the frame may be made of a single piece casting if desired.

It will be seen from the foregoing description that by use of this invention, a double end dumping car is provided which permits the car body to be dumped at either end of the car frame from the opposite end, at any part of the train, thereby avoiding the present necessity of having single end dumping cars at the end of the train. Furthermore, by use of this invention a considerable amount of switching and turning of the car will be avoided, since end dumping cars of this type can be coupled from either end.

Modifications and changes in the specific construction here described can be made without departing from the scope of the invention.

Having thus described my invention, what I claim as new and desire to secure by Letters Patent, is:

1. The combination with a car frame and a car body mounted to move within the frame in opposite directions from a central upright position, of means for tilting the car body to discharge the contents through the frame.

2. The combination with a car frame, of a car body mounted to simultaneously tilt and move bodily within the frame.

3. The combination with a car frame having its interior portion unobstructed, of a tilting and longitudinally movable car body mounted thereon adapted to be tilted to discharging position entirely within the frame.

4. The combination with a car frame having side tracks, of a tilting car body mounted thereon, means for tilting said body in either direction from a central upright position, and operable from either end of the car body.

5. The combination with a car frame having side tracks, of a tilting and longitudinally movable car body mounted thereon, means for tilting said body in either direction from a central upright position, and operable from either end of the car body.

6. The combination with an end dumping car body, of a frame inclosing the car body in both upright and dumping positions, and

mechanical actuating means mounted on the frame for operating the car-body.

7. The combination with an end dumping car body, of a frame inclosing the car body in both upright and dumping positions, and having operating means at each end. 65

8. The combination with a car frame having a tilting and longitudinally moving car body mounted thereon, of means engaging the car-body support for tilting and longitudinally moving the car body toward either 70 end of the car frame.

9. The combination with a car frame having opposite side frames provided with tracks, of a car body mounted to roll thereon and discharge within the side frames, a screw 75 shaft mounted on one of the side frames, a nut mounted thereon and having actuating connection with the car body, and means for turning the shaft to actuate the car body.

10. The combination with a car frame 80 having opposite side frames provided with tracks, of a car body mounted to roll thereon in either direction from a central upright position to discharge within the side frames, a screw shaft mounted on one of the side 85 frames, a nut mounted thereon and having actuating connection to move the car body in either direction, and means for turning the shaft to actuate the car body.

11. The combination with a car comprising connected side frames having tracks, of a tilting car body, trunnions on the car body mounted on said tracks, and means for simultaneously tilting and moving the car body for dumping toward the end within the 95 frame.

12. The combination with a car comprising connected side frames, of an end dumping car body, a trunnion supported on the car frame and carrying said car body, and a 100 screw engaging the trunnion for simultaneously tipping and moving the car body toward the end, said car body dumping within the frame, and coupling means carried by the end of the frame. 105

13. The combination with a movable car body mounted between rigidly connected side frames and supported thereby, of means for simultaneously moving and tilting the body to a discharging position toward one 110 end of the frame from the center, and coupling means at the discharging end.

In testimony whereof I affix my signature, in presence of two witnesses.

EDWIN E. SLICK.
